UNITED STATES PATENT OFFICE

135,291

DESIGN FOR A CIGARETTE TRAY

Maurice J. Fletcher, Des Moines, Iowa, assignor to Cadet Smokestands Company, Des Moines, Iowa

Application May 9, 1942, Serial No. 106,947

Term of patent 14 years

To all whom it may concern:

Be it known that I, Maurice J. Fletcher, a citizen of the United States and resident of Des Moines, Polk County, Iowa, have invented a new, original, and ornamental Design for a Cigarette Tray, of which the following is a specification, reference being had to the accompanying drawing, forming a part thereof.

Fig. 1 is a front elevational view of a cigarette tray showing my new design.

Fig. 2 is a side elevational view; and

Fig. 3 is a top plan view thereof.

I claim:

The ornamental design for a cigarette tray, substantially as shown.

MAURICE J. FLETCHER.
